UNITED STATES PATENT OFFICE

2,646,310

STAKE BODY

Benjamin F. Leber, Chicago, Ill.

Application June 17, 1949, Serial No. 99,773

1 Claim. (Cl. 296—28)

1

This invention relates to wagon and trailer and the like movable and stationary bodies, and is concerned more particularly with stake bodies.

Conventional stake bodies, both industrial and toy, are designed without much, if any, regard to appearance, and are made with stakes and sockets which form a number of unsightly and injurious projections.

It is accordingly an object of my invention to provide a stake wagon body free of the foregoing disadvantages.

It is also an object to provide a rail or slat combined with stakes of novel construction.

Another object is to provide a stake body such that the slats may be more expeditiously mounted on and removed from the box.

A further object is to provide a stake wagon body in which none of the stakes, sockets therefor and slats extends substantially outside of the projected outer vertical planes of the box panels.

An additional object is to provide a stake body in which none of the stakes, sockets therefor and slats extends inward relative to the projected inner vertical planes of the box panels.

Further objects and advantages of the invention will appear as the description proceeds.

The invention will be better understood upon reference to the following description and accompanying drawing, in which:

Fig. 1 is a top plan view, partly in section, of a stake body embodying features of my invention.

Fig. 2 is a side elevational view, partly in section, of the same.

Fig. 3 is a front end elevational view of the same.

Figs. 4 and 5 are fragmentary enlarged sectional views taken as indicated by the lines 4—4 and 5—5, respectively, in Fig. 2.

Referring now more particularly to the drawing, showing an illustrative embodiment of the invention, there appears generally at 10 an open-topped box comprising side panels 12 having inner vertical slots 14 near the ends 16 thereof and also having lower longitudinal grooves 18; front and rear panels 20 and 22, respectively, with their ends 24 fitted in the vertical slots and with lower inner longitudinal grooves 26 at the same level as and communicating with the grooves 18; and a floor board 28 whose margins 30 are fitted in the grooves of the respective panels. The various parts thus far described are assembled by first fitting the front and rear margins of the floor board 28 into the grooves 55 above the adjacent portions of the side slats 57.

2

26 of the front and rear panels 20 and 22 and then moving the side panels 12 laterally toward the same so as to fit the ends 24 of the front and rear panels into the slots 14 and the side margins of the floor board into the side panel grooves 18. The assembly of panels and floor board is held rigid as by tie rods 38 passing through holes 40 in the side panels 12 and nested in longitudinal inner half-round grooves 42 in the front and rear panels 20 and 22, each tie rod having a head 44 which may be separated from the adjacent side panel by a washer 46, the opposite end of each tie rod being threaded and receiving a nut 48 which may be separated from the adjacent side panel by a washer 46.

For the purpose of detachably connecting side and front slats to the respective box panels to provide a stake body, I bore holes 52 in the various panels and line the walls of said holes 20 with sleeves 54, forming sockets 56. Secured to the inner sides of the side slats 57 and front and rear slats 58 and 60 are inverted U-shaped stake members 62 of preferably round steel or other suitable rod stock, depressed as at 63 to provide 25 spaced flattened portions 64 through which extend screws 66 threaded into the slats, whereby the stake members are securely anchored to the slats. The screw heads 68 preferably lie entirely within the respective depressions 63 so that they will not snag on the person or clothing of anyone 30 riding in or any object carried by the wagon. The arms 68 of each stake member 62 serve as stakes and project below the slats a distance which is preferably substantially greater than the depth of the sockets 56 and fit snugly and 35 slidably therein, so that, when the slats are mounted, they are elevated a substantial distance, indicated at 72, from the panels. Where, as shown, the side panels 12 are substantially longer than the front and rear panels 20 and 22, the slats 57 are correspondingly longer than the front and rear slats 58 and 60, so that two stake members 62 are secured to each side slat. All 40 of the stake members 62 are preferably identical, so that, if desired, each side slat may be replaced by two slats in tandem.

The various slats are preferably formed of the same flat wood or other suitable stock and are preferably substantially thinner than the box panels. If desired, the slats may rest on or be spaced at any desired distance above the panels, and the side slats may be of the same height throughout or have any desired shape. The front and rear slats 58 and 60 preferably do not project 50 above the adjacent portions of the side slats 57.

The arrangement of the parts is preferably such that, with the various slats in place, the outer surfaces 82 of the slats are substantially flush with the outer surfaces 84 of the panels. The free ends of the stakes 68 may be rounded as indicated at 86 and the stakes may be somewhat flexible to facilitate their entry into the sockets 56.

It is apparent from the foregoing that I have provided a stake body which may form part of a wagon, trailer, bin or serve any other suitable purpose, and which is substantially entirely free of outside and inside projections, presenting a neat appearance, and that the various slats are firmly yet detachably anchored to the panels and will not rattle.

Various modifications coming within the spirit of my invention may suggest themselves to those skilled in the art, and hence I do not wish to be limited to the specific form shown or uses mentioned, except to the extent indicated in the appended claim, which is to be interpreted as broadly as the state of the art will permit.

I claim:

A stake body comprising a box having side and end panels, tie members passing through two opposite panels and embedded in the inner faces of the other two panels, all of said panels having longitudinally spaced pairs of vertically elongated upper sockets between the inner and outer faces thereof, said two opposite panels having vertical inner notches in which the ends of the other panels are seated, all of said panels having together a continuous horizontal groove, a floor board marginally seated in said con-

tinuous groove, a slat associated with each panel, planar inverted U-shaped rods of circular cross-section and having spaced flat portions, fastening means passing through said flat portions and securing said rods to the inner sides of said slats, said fastening means being disposed entirely within the confines of said rods and slats, said rods serving as stakes projecting below said slats and removably slidably engaged snugly in said pairs of sockets, said flat portions being in flatwise engagement with said inner faces of said slats, said stakes being of greater length than said sockets, whereby, when said stakes are fully projected into said sockets, said slats are spaced above said panels.

BENJAMIN F. LEBER.
